R. BARTON.
TRENCH DIGGING MACHINE.
APPLICATION FILED SEPT. 15, 1919.

Patented Nov. 23, 1920.

UNITED STATES PATENT OFFICE.

ROBERT BARTON, OF CLIFFORD, ONTARIO, CANADA.

TRENCH-DIGGING MACHINE.

1,359,781.

Specification of Letters Patent. Patented Nov. 23, 1920.

Application filed September 15, 1919. Serial No. 323,930.

To all whom it may concern:

Be it known that I, ROBERT BARTON, of the town of Clifford, in the county of Wellington, Province of Ontario, Canada, have 5 invented certain new and useful Improvements in Trench-Digging Machines, of which the following is the specification.

My invention relates to improvements in trench digging machines and the object of 10 the invention is to devise a simple device whereby a trench may be quickly and easily dug with a minimum amount of labor and it consists essentially of the following arrangement and construction of parts as hereinafter more particularly explained.

Figure 1, is a perspective view of my device.

Fig. 2, is a perspective detail of the scoop employed in connection with my device and 20 the adjacent parts.

Fig. 3, is a perspective detail of one of the gear wheels employed in connection with the operation of my device.

Fig. 4, is a detail view disclosing the 25 means for locking the adjusting lever of the elevating conveyer in the desired position.

In the drawing like characters of reference indicate the various parts in each figure.

1 indicate the main frame which is provided with a front axle 2, a rear axle 3 rotatably mounted in suitable bearings carried by the bars 4 and 5 of the frame. 6 is the forward carrying wheel which is secured 30 upon the axle 2. 7 is the rear carrying wheel which is secured to the axle 3 and the periphery of which is provided with cork projections 8. 9 is a shaft which is journaled in the side bars 4 and 5 in proximity to 35 the rear wheel 7. 10 is a groove pulley secured to the shaft 9 at the inside of the side bar 4 of the main frame. 12 is a bar which is secured in a vertical position of the side bar 4 adjacent to the pulley 10. 13 and 14 40 are groove rollers mounted upon the bar 12 at each end thereof so as to partially project over the periphery of the pulley 10. 15 is a grooved pulley secured to the axle 3. 16^x is a cable drive which extends around the 45 pulley 15, around the groove rollers 13 and 14 so as to bear against the periphery of the pulley 10. 16 is an elevating conveyer which is pivotally mounted intermediate of its length upon the shaft 9. The conveyer 50 16 comprises a bottom board 17, side boards 18 and 19 on the upper end of which is journaled a shaft 20 and at the lower end of which is journaled a shaft 21. 22 is a sprocket gear mounted upon the shaft 20 between the side boards 18 and 19 and 23 is 55 a sprocket gear mounted upon the shaft 21 between the side boards 18 and 19 and provided with sprocket chain 24. 25 is a pulley mounted upon the shaft 20. 26 is a cable drive extending around the pulley 25 and 60 around the pulley 11. By this means when the rear wheel 7 travels in the direction of the arrow indicated in Fig. 1, the chain 24 is carried in the direction of the arrow (see Fig. 1, also) so that the dirt which is 65 fed onto the conveyer as hereinafter described is carried upwardly by the links of the conveyer and discharged at the upper end. 27 is a scoop which is secured to the lower end of the side boards 18 and 19. The 70 scoop 27 comprises side plates 28 and 29 provided with upwardly extending arms 30 and 31 which extend between the side bars 4 and 5 of the main frame thereby forming a guide for the lower end of the conveyer when adjusted vertically. Between the plates 28 and 29 is secured the scoop proper 30^x. As will be seen in reference to 75 Fig. 2, the lower end of the scoop 30^x is secured between the lower end portions of 80 the side plates 27 and 28. The opposite end inclines upward over the lower end of the chain conveyer 24 so that the earth that is picked up by the scoop is carried direct on to the links of the chain between the side 85 boards 18 and 19. In order to adjust the lower end of the conveyer I have provided a shaft 32 journaled in suitable bearings. Mounted upon the shaft 32 is secured a drum 33. 34 is a chain which is secured to 90 the periphery of the drum 33 at one end and at the opposite end to a cross bolt 35 extending through the arms 30 and 31. 35^x is an arc-shaped bar which is secured to the side bar 4 of the main frame so as to be 95 concentric with the shaft 32. 36 is a lever which is secured to the shaft 32 so as to extend upwardly in a radial position. The lever 36 is provided with a plate finger 37 100 extending over the bar so as to form a guide for the lever 36. The bar 35 is provided with a series of perforations 38. 39 is a supplemental lever pivotally mounted in the bracket 40 carried by the lever 36. The lower end of the lever 39 is provided with 105 a plunger pin 41 which passes through an orifice 42 in the lever 36 and at the end

- through a perforation 38 in the bar 35. The drum 33 is turned so as to wind or unwind the chain 34 thereon, thereby adjusting the position of the scoop 27. 43 is a runway which is supported by a bracket 44 carried by the main frame. The runway 43 is directed laterally so that the earth discharged from the conveyer 16 is deposited at the side of the trench as the trench is dug. In order to support my machine in a vertical position I have provided a side frame 45 which extends laterally from the main frame and at the outer end of the frame 45 is secured a vertical guideway 46. 47 is a side bar slidably held in the guide 46 in the lower end of which is supported an axle 48 upon which is mounted a wheel 49. 50 is a vertical rack which is formed integral with the side bar 47. 51 is a gear mounted upon the shaft 52 journaled in a suitable bearing carried by the side frame 45. The gear 51 is formed in two portions 53 and 54, the portion 53 being in the form of a worm gear and the portion 54 in the form of a straight gear engaging the rack 50. 55 is a shaft journaled in the bearings 56 and 57 carried by the frame 45. The inner end of the shaft 55 is provided with a crank wheel 58 by which the shaft is turned, the outer or opposite end being provided with a worm 59 engaging the worm gear portion 53 of the gear 52. By turning the crank wheel 58 the shaft 55 is drawn together with the worm 59 which engages the worm gear portion 53 turning the gear wheel 53 thereby revolving the gear portion 54 in engagement with the rack and thereby elevating or lowering that side of the machine according to requirements. The machine is drawn over the surface of the ground by horses or by a suitable tractor, the scoop 27 being lowered into contact with the ground and taking up a layer of earth which is deposited by the scoop upon the chain 24 which conveys the earth upwardly and deposits it upon the runway 43 so that it falls at the side of the trench as it is dug. This operation is repeated, the scoop being gradually lowered at each operation.
- From this description it will be seen that I have devised a very simple form of trench digging machine which will quickly form a trench, cutting it to the required depth. It will of course be understood that the depth of the trench should be regulated by the size of the carrying wheels of the machine which would provide the greater or less vertical space through which the scoop of the conveyer might be adjusted.
- What I claim as my invention is.
1. A trench digging machine comprising

a main frame, a front carrier wheel and a rear carrier wheel, a conveyer swingably held in the main frame between the front and rear carrier wheels, a scoop at the lower end of the conveyer, a laterally extending inclined runway carried by the main frame, beneath the upper end of the conveyer and a supplemental frame secured to the main frame and extending laterally therefrom at the opposite side to the discharge, a vertical guideway carried by the supplemental frame at the outer end, a slide bar carried in the vertical guideway, a carrier wheel carried by the lower end of the side bar, and means operated from the center of the machine for adjusting the slide bar vertically.

2. A trench digging machine, comprising a main frame, a front carrier wheel and a rear carrier wheel, a conveyer swingably mounted in the main frame between the front and rear carrier wheels, a scoop at the lower end of the conveyer, a laterally extending inclined runway carried by the main frame beneath the upper end of the conveyer and a supplemental frame at the opposite side of the discharge pipe, a vertical guideway carried by the supplemental frame at the outer end, a slide bar carried in the vertical guideway, a carrier wheel carried by the lower end of the slide bar, a vertical rack carried by the slide bar, a gear wheel mounted in the supplemental frame and comprising a worm wheel portion, and a straight gear portion meshing with the rack, a worm shaft journaled in the supplemental frame and provided at one end with a worm and at the opposite end with an operating crank wheel.

3. A trench digging machine comprising a main frame provided with front and rear carrier wheels, a conveyer and a scoop therefor supported by said main frame, an auxiliary frame extending laterally from the main frame, and adjustable supporting means carried by the auxiliary frame for maintaining the main frame and the conveyer in upright operative position.

4. A trench digging machine comprising a wheeled main frame, a conveyer and a scoop supported thereby, an auxiliary frame extending from the main frame, vertically adjustable supporting means carried by the outer end of the auxiliary frame for maintaining the main frame and the conveyer in upright or operative position, and mechanism for adjusting said supporting means mounted on the said auxiliary frame.
